DESIGN FOR A TRICYCLE

Raymond R. Taylor, Brooklyn, Mich.

Application March 25, 1947, Serial No. 137,859

Term of patent 3½ years

(Cl. D34—15)

To all whom it may concern:

Be it known that I, Raymond R. Taylor, a citizen of the United States, residing at Brooklyn, in the county of Jackson and State of Michigan, have invented a certain new, original, and ornamental Design for a Tricycle, of which the following is a specification, reference being had to the accompanying drawing, forming part thereof.

In the drawing:

Fig. I is a front view in elevation of such a tricycle,

Fig. II is a side view in perspective of such a tricycle, and

Fig. III is a top view of a tricycle constructed according to my design.

I claim:

The ornamental design for a tricycle, substantially as shown and described.

RAYMOND R. TAYLOR.
